UNITED STATES PATENT OFFICE.

WILLIAM H. SMITH, OF MILWAUKEE, WISCONSIN.

ABRADING-MACHINE.

1,390,828.

Specification of Letters Patent. Patented Sept. 13, 1921.

Application filed January 13, 1921. Serial No. 436,897.

To all whom it may concern:

Be it known that I, WILLIAM H. SMITH, a citizen of the United States, and resident of Milwaukee, in the county of Milwaukee and State of Wisconsin, have invented certain new and useful Improvements in Abrading-Machines; and I do hereby declare that the following is a full, clear, and exact description thereof.

- 10 My invention relates to new and useful improvements in abrading machines and has special reference to those machines which employ sand or emery covered disks having flat operating surfaces.
- 15 The principal object of this invention is to provide a machine of this character with a work support having means whereby the table surface thereof can be disposed at practically any desired angle to the flat operating face of the abrading member.
- 20 It is further an object of this invention to provide means for conveying the material removed from the articles operated upon to a suitable storage space within the supporting base or pedestal of the machine.

An additional object of this invention is to provide a simply constructed support, having means for mounting a pair of abrading members together with means for simultaneously operating the latter and suction fans which are used for carrying out the last mentioned object of the invention.

With these general objects in view, the invention resides in the novel features of construction, combination and arrangement of parts which will be hereinafter more particularly described and claimed and shown in the accompanying drawings in which

Figure 1 represents a part elevational and part sectional view through a machine constructed in accordance with the invention, said section being taken substantially on the plane of the line 1—1 of Fig. 2, and

Fig. 2 is a side elevational view of a machine, parts being broken away and parts in section.

In these drawings the main features of the invention are shown in a machine provided with a pair of abrading members, but it is obvious that they may be employed in connection with single wheel machines, or those having a plurality of such wheels or abrading members.

Consequently various changes may be made in the form and proportions of the different parts of the illustrated structure,

without departing from the principles of the invention or sacrificing any of its advantages.

Referring more particularly to the drawings, it will be seen that the reference character 1 denotes a hollow supporting base or pedestal having a cleanout opening normally covered by a plate 2 and having a pair of spaced bearing supports 3 on its top. These supports 3 mount a pair of spaced bearings 4 in which the opposite ends of a shaft 5 are journaled. The intermediate portion of the shaft in the space provided between the bearings 4 has a drive pulley 6 secured thereto to permit the machine to be operated by a suitable drive belt, and also formed on the intermediate portion of the shaft 5 is a second or driving pulley 7 of smaller diameter than pulley 6.

The opposite ends of the shaft 5 project beyond the outer ends of the bearings 4 and have circular abrading wheels or disks 8 detachably mounted thereon. As is customary in machines of this character, the outer flat faces of each of the wheels 8 is covered with an abrading material such as sand or emery. Thus the single shaft 5 simultaneously drives a pair of abrading members, and two workmen can be employed on a single machine at the same time.

The articles which are operated upon by the abrading wheels 8, are supported upon tables 9, one of which is located adjacent the working face of each wheel. Inasmuch as the structure at each side of the machine is identical, it is necessary to describe but one part thereof. With such information in view, it will be seen that the table 9 is secured upon the outer end of a curved supporting bar 10, the point of engagement with the table being at its outer edge portion. In other words the inner edge of the table is unsupported and is adjacent the working face of the co-operating abrading wheel 8, such edge is always spaced slightly below the center of rotation of the wheel. The bar 10 is slidable in an elongated guide 11 carried by one side of the base 1 and having arcuate ribs 12 for engagement in the grooves 13 of the bar. The guide 11 is also provided with a lock plate 14 which is adapted to engage one side of the bar 10, and when moved in the proper direction by the rotation of a handle 15 will clamp the bar against the opposite side of the guide and retain the same in rigid position. In

view of the fact that the center of the arc on which the bar 10 is formed coincides with the inner or free edge of the table 9, the surface of the latter may be moved to any angle 5 within a range of nearly 180 degrees with the flat working face of the wheel 8. This movement of the table, of course, is procured when the bar 10 is permitted to slide through the guide, the table being rigidly held in the 10 adjusted position when said bar 10 is clamped in its guide.

The lower portion of the wheel 8 rotates in a suitable receiving receptacle 16 formed in a suitable receiving receptacle 16 formed of inner and outer walls 17 and 18 respectively, the latter of which is readily removable and forms a cover plate. The lower end of the receptacle 16 has an enlarged circular outlet opening 19 which extends laterally and opens through one wall of the support- 20 ing base 1.

The outlet passages 19 of the illustrated embodiment of the invention are disposed on opposite sides of the base and are axially aligned. The opposite ends of a shaft 20 are 25 journaled in bearings 21 formed in these passages 19, and said ends are each provided with a suction fan 22. The intermediate portion of the shaft 20 extends through the lower end of a belt pocket 23 and carries 30 within said pocket a pulley 24. The pulley 7 and the last mentioned pulley 24 are aligned

and adapted to have a suitable belt trained therearound whereby the shaft 20 and the suction fans 22 will be simultaneously actuated with the abrading members 8. Obviously as material is removed from the articles supported on the tables 9 by the abrading members 8, it is sucked into the receiving receptacles 16 and from there through into the hollow base 1, which forms 40 a storage compartment.

I claim:

In a device of the character described, a rotatable shaft, an abrading disk carried at each end thereof, a housing surrounding 45 the lower portion of each disk, a bifurcated receptacle between the housings, a passageway connecting each housing with the receptacle, a second shaft extending through the furcations of the receptacle parallel to 50 the first shaft and having its ends projecting into the passageways, means on the second shaft between the furcations for forming a driving connection with the first shaft, and a fan mounted on each end of the second 55 shaft for blowing the dust from the disks into the receptacle.

In testimony that I claim the foregoing I have hereunto set my hand at Milwaukee, in the county of Milwaukee and State of 60 Wisconsin.

WILLIAM H. SMITH.
